(57) **CLAIM**

The ornamental design for a portable wireless communication device, as shown and described.

DESCRIPTION

FIG. 1 is a perspective view of front, right and top of portable wireless communication device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures that are immediately adjacent to the shaded areas and define regions that are unshaded, represent the bounds of the claim, while all other broken lines are directed to portions of the portable wireless communication device that do not form a part of the claimed design. The broken lines form no part of the claimed design.
